BINDING MACHINE

Christian B. Nelson and Isidore Spinner, Chicago,
Ill., assignors, by mesne assignments, to Plastic
Binding Corporation, Chicago, Ill., a corpora-
tion of Delaware

Application March 23, 1936, Serial No. 70,355

13 Claims.

(Cl. 11—1)

The present invention relates generally to a binding mechanism, and more particularly to a novel mechanism for spreading an elastic tubular binder for the purpose of inserting a pack of perforated sheets to be secured by the binder, to obtain a book of sheets or pages, of the type shown and described in United States Letters Patent No. 1,970,285, dated August 14, 1934, granted to R. M. L. Douvry.

10 The binder comprises a continuous back portion having a number of fingers extending from one longitudinal edge thereof, and made of a material, such as celluloid, or pyroxylin, for example, that can be curled longitudinally into a tubular form, and which has sufficient elasticity 15 to cause it to reassume its tubular form whenever it is spread open and released.

20 The principal object of this invention relates to the provision of a mechanism or apparatus to facilitate spreading open such a binder, holding it in uncurled position while a pack of perforated sheets is placed in proper position for binding, and gradually releasing the binder, allowing it to recur as the fingers are inserted through the 25 perforations in the sheets.

25 A further object relates to the provision, in such a machine, of means for adjustably setting the parts thereof to accommodate binders of different sizes.

30 The attainment of the above and further objects of the present invention will be apparent from the following specification taken in conjunction with the accompanying drawings forming a part thereof.

35 In the drawings:

Figure 1 is an isometric view of an elastic binder of the type mentioned above;

Figure 2 is an end elevation of a machine embodying the principles of the present invention, showing the mechanism in normal, or released 40 position;

Figure 3 is a front elevation of the machine shown in Figure 2;

Figure 4 is a sectional elevation taken along the line 4—4 of Figure 3;

Figure 5 is a top view or plan of the same machine; and

Figure 6 is a detail of the removable spreader pin used in the machine.

50 Like reference numerals refer to like parts throughout the specification and drawings.

Referring to Figure 1, the binder 1 consists of a band or strip forming a back portion 2, and a plurality of spaced apart fingers 3. The binder 55 is made of suitable material which can be curled

into a longitudinal tubular form as shown, and which has sufficient flexibility to permit spreading it open, and sufficient elasticity to cause it to recur when released. It has been found that a certain type of cellulosic material can be curled 5 into this shape when heated, and after cooling retains that shape.

Referring now to the several views of the spreading apparatus, a supporting base 4 supports a working plate 5, which, for convenience of manufacture is made in two parts, a front plate 6, and a rear plate 7, both of which are secured to the base by suitable means, such as screws 8 (Fig. 5).

A plurality of pins 9 are fixed in a row on the 15 rear plate 7, and arranged with suitable spacing to conform with the spacing between the fingers 3 on the binder 1, as will be explained later.

Substantially parallel to the row of pins is a backing plate 10 which is a part of a base plate 20 11. The base plate is adjustably slidable on the working plate 7 and secured in fixed position by means of thumb screws 12, which extend through slots 13 in the base plate 11 and screw into tapped holes in the working plate 7. After loosening 25 these thumb screws, the backing plate 10 can be set closer to, or farther from the row of pins, for purposes to be explained later.

A number of slots 14 are cut in the rear working plate 7, these slots being suitably spaced relative to the pins. In each slot is disposed a vertically extending spreader hook 15, which has a hook 16, on the upper end of a rectangular shank 17 projecting above the surface of the plate 7. Each of the shanks 17 is securely held in a supporting structure 18 comprising a pair of plates 19 having opposing notches 20, (shown in the broken away portion in Figure 5, with the hook omitted), within which notches the shanks of the spreader hooks 15 are clamped. The plates 19 40 are held together by bolts 21. Hence it is evident that the hooks 16 are maintained in alignment by the supporting structure 18, and are disposed in a row parallel to the row of pins 9. By actuating the supporting structure the hooks 45 15 can be moved in unison in the slots 14, toward or away from the row of pins 9.

The hook supporting structure 18 is mounted on a pair of rack members 22, and secured by nuts 40, said members each comprising a rack 50 23 and extension rods 24 and 25. One of the extension rods 24 is carried in a bearing 26 in the supporting frame, and has a threaded end, which is provided with a pair of adjusting lock nuts 27. The other extension rod 25 extends 55

into a socket 28 in the supporting frame 4. A compression spring 29 is disposed on the extension 25 and operates to maintain the rack normally in the extreme position toward the left, as shown in Figure 2. The rack member is partly supported by a second bearing 30.

Meshing with the rack 23 are pinions 31, mounted on a through shaft 32, which is carried in bearings 33, 34 at each end respectively of 10 the supporting base 4. A crank 35 is fixed to one end of the shaft 32 and is rotated angularly by an operating rod 36 jointed thereto.

Normally, the apparatus is in the position shown in Figure 2, the row of hooks being near 15 and in alignment with the row of pins. When the operating rod is actuated, preferably by a foot pedal (not shown), the pinions 31 are rotated, (clockwise as seen in Figures 2 and 4) thereby moving the rack member 22 and thus 20 the supporting structure 18 with its row of hooks 15, toward the right to the position illustrated in Figure 4. The extent of this movement can be adjusted by screwing the lock nuts 27 in or out on the extension rods 24. When the foot 25 pedal is released, the springs 29 return the rack members 22 to the left as shown in Figure 2.

The method of operating this device will now be explained. The first step is illustrated in Figure 2.

30 The binder 1 is laid on the working plate 7 with the back portion 2 held between the backing plate 10 and the row of pins 9. The pins are spaced so that they stand in spaces between fingers 3 of the binder 1. The backing plate 10 is set at such a distance from the pins 9 that it will hold the back portion 2 against the pins 9.

With the rack 22 in the extreme left position as shown, each of the hooks 16 is in a space between fingers 3 of the binder 1. Certain of the 40 spaces between fingers 3 now are occupied by pins 9 while other spaces between fingers are occupied by hooks 16. The spacing of hooks and pins may be such that every space between fingers is occupied by either a hook 16 or a pin 9 45 but this is not essential, as the spacing can be made such that there are some unoccupied spaces between fingers 3.

A rod or wire 37 is now inserted axially through the tubular binder 1 and under the hooks 16, 50 that is to say, between the hooks and the inside surfaces of the fingers 3. The rod 37 is shown separately in Figure 6.

By actuating the operating rod 36, the hooks are moved to the right, to the position indicated 55 in Figure 4, thus moving the rod 37 away from, but parallel to the row of pins 9. Since the back portion 2 of the binder 1 is held substantially fixed between the pins and the backing plate 10, the fingers 3 are thus uncurled, until in the final 60 position, they are spread open, as illustrated in Figure 4. A pack of perforated sheets or pages 38 are then placed in proper position for binding, with the aligned perforations 39 in register with the ends of the uncurled fingers 3.

65 The control lever 36 is then gradually released, and the spring 29 forces the supporting structure 18 back toward the original position. As the rod 37 moves back, the fingers 3 recurl, and in so doing, the ends of the fingers are inserted into and through the aligned perforations 39, and finally return to a normal curled position within the back portion 2, being guided into that position by the stack of pages being bound.

70 The rod 37 is then withdrawn from the end of

the binder 1 and the assembled book lifted off the pins 9.

An assembled book can be disassembled in a similar manner. The book is first pressed down on the pins, which must, of course, be inserted 5 between the fingers as before, and between the pack of sheets 38 and the back portion 2. The rod 37 is then inserted axially through the binder, under the hooks 16, and then by actuating the operating rod 36 as before, the fingers 10 are spread open, the ends of the fingers being thereby withdrawn from the perforations. After lifting the pack of sheets away from the binder, the operating rod 36 is released, allowing the empty binder to recurl. The rod 37 is then withdrawn, and the binder can be lifted from the pins.

The lock nuts 27 should be set for each size of binder so that the motion of the mechanism will be limited to such an extent that the fingers 20 will be spread sufficiently to permit insertion of the pack of sheets, but without allowing the ends of the fingers 3 to escape from under the rod 37.

In compliance with the requirements of the patent statutes there has been shown and described a preferred embodiment of the present invention. It is, however, to be understood that the invention is not limited to the precise machine here shown, the same being merely illustrative of the principles of the invention. What 30 is considered new and desired to be secured by Letters Patent is:

1. Apparatus for assembling a pack of perforated sheets into an elastic binder having a continuous back portion with curled fingers forming a closed circle with said back portion and adapted for engagement with aligned perforations in said pack of sheets, said apparatus comprising in combination, means for holding said back portion, and means for moving said fingers to their uncurled position and holding said fingers uncurled to permit insertion of a pack of sheets in proper position for binding.

2. Apparatus for assembling a pack of sheets into a tubular elastic binder having a continuous back portion with a plurality of curled fingers extending therefrom and forming a closed circle with said back portion, said fingers being adapted for engagement through corresponding aligned perforations in said pack of sheets, said apparatus comprising in combination, means for holding said back portion in fixed position, movable means for engaging said fingers, and means for moving said movable means to uncurl said fingers, whereby a pack of perforated sheets may 55 be placed in binding position, so that upon release of said movable means the fingers pass through said perforations as the fingers recurl.

3. Apparatus for assembling a pack of sheets into a tubular elastic binder having a continuous back portion with a plurality of curled fingers extending therefrom, said fingers being adapted for engagement through corresponding aligned perforations in said pack of sheets, said apparatus comprising in combination, means for holding said back portion in fixed position, means for uncurling the fingers; said uncurling means including spreader hooks extending between fingers of the binder, a common support for all the spreader hooks, and means for actuating the support to move the hooks.

4. Apparatus for assembling a pack of perforated sheets into a tubular binder having a back portion with a plurality of curled elastic fingers extending therefrom, said fingers being adapted 75

for engagement with corresponding aligned perforations in said pack of sheets, said apparatus comprising in combination, means for holding said back portion in substantially fixed position, a rod adapted for insertion axially through said tubular binder, and means for moving said rod away from, but substantially parallel to said back portion, thereby uncurling said fingers, for insertion of a pack of sheets in proper position for binding, whereby upon release of said fingers they are guided through said perforations during recurring.

5. Apparatus for assembling a pack of perforated sheets into a tubular binder having a back portion from which extend a plurality of elastic curled fingers adapted for engagement with corresponding aligned perforations in said pack of sheets, said apparatus comprising in combination, means including a row of pins for holding 10 said back portion between said fingers, in substantially fixed position, a rod adapted for insertion axially through said tubular binder, a plurality of hooks for engaging said rod between said fingers, supporting means for said hooks, and means for actuating said hooks to move said rod away from, but parallel to said back portion, thereby uncurling said fingers, for holding said fingers incurled to permit insertion of a pack of sheets in proper position for binding, so that upon 15 release of said fingers under control they can pass through said perforation upon recurring.

6. Mechanism for spreading a tubular binder for inserting a pack of perforated sheets therein, said binder having a continuous back portion 20 from which extend a plurality of curled elastic fingers adapted for engagement with corresponding aligned perforations in said pack of sheets, said mechanism comprising means including a backing member and a row of pins for holding said back portion in substantially fixed position, each of said pins extending between fingers, a rod for insertion axially through said tubular binder, a plurality of hooks, each of said hooks engaging said rod, and means for moving said hooks, in unison, in a direction perpendicular to said row of pins to a predetermined distance from 25 said pins.

7. A device for spreading a cylindrical elastic binder which has a plurality of binding fingers, said device including means for holding the binder in position, a plurality of spreader hooks extending between the fingers of the binder, and means for uncurling the fingers, said means including said spreader hooks and means for moving the same.

55 8. A device of the class described, comprising a backing member, a row of spaced apart pins substantially parallel thereto, a plurality of spreader hooks disposed in alignment parallel to said row of pins, and means for moving said hooks in unison toward or away from said row of pins.

9. In a device of the class described, a row of pins, a backing member disposed parallel thereto, means for adjusting the distance between said backing member and said row of pins, a plurality of hooks, a removable rod adapted to be engaged by all of said hooks simultaneously, a common supporting structure for said hooks, and means for moving said structure in a direction perpendicular to said row of pins.

10. A device of the class described, comprising in combination a working plate, a row of spaced-apart pins fixed thereto, a backing member disposed parallel to, and spaced from, said row of pins, said plate having a row of spaced-apart slots, disposed substantially perpendicular 15 to said row of pins, a plurality of spreader hooks, each of said hooks extending through one of said slots, respectively, a movable spreader hook supporting structure beneath said plate, and means for actuating said supporting structure to move 20 said hooks in said slots.

11. A device of the class described, comprising in combination a working plate, a row of spaced-apart pins fixed thereto, a backing member disposed substantially parallel to said row of pins, 25 means for adjusting said member relative to said pins, said plate having a plurality of slots therein, said slots being disposed between said pins in spaced relation thereto and perpendicular to said row of pins, a plurality of spreader hooks supported in alignment by a common structure disposed beneath said plate, each of said hooks extending through one of said slots, respectively, means for actuating said hook supporting structure to move said hooks from a position adjacent 30 said row of pins, spring means for returning said hooks to said position, and means for adjustably limiting the extent of said motion.

12. Mechanism for spreading a binder of the type having a plurality of spaced parallel curled 40 elastic fingers held together by a longitudinally extending portion from which the fingers extend, said mechanism comprising means for holding the longitudinally extending portion, and means adapted to engage the fingers and movable away 45 from the longitudinally extending portion for uncurling the fingers.

13. Mechanism for spreading a binder of the type having a plurality of spaced parallel curled elastic fingers held together by a longitudinally 50 extending portion from which the fingers extend, said mechanism comprising means for holding the longitudinally extending portion, and means adapted to engage the fingers and movable away from the longitudinally extending portion 55 for uncurling the fingers, said last means including a plurality of spreader hooks disposed in alignment parallel to said held longitudinally extending portion of the binder and movable towards and away therefrom.
